United States Patent Office.

WILLIAM WILSON, OF GALESBURG, ILLINOIS.

Letters Patent No. 77,152, dated April 21, 1868.

IMPROVEMENT IN SLIDE-VALVES.

The Schedule referred to in these Letters Patent and making part of the same.

TO ALL WHOM IT MAY CONCERN:

Be it known that I, WILLIAM WILSON, of Galesburg, in the county of Knox, and State of Illinois, have invented a new and useful Improvement in Steam-Valves; and I do hereby declare that the following is a full, clear, and exact description thereof, which will enable those skilled in the art to make and use the same, reference being had to the accompanying drawings, forming part of this specification.

This invention relates to a new and improved construction of the slide-valves of steam-engines, whereby double openings are given both at steam and exhaust-ports.

In the accompanying plate of drawings—

Figure 1 represents a central vertical section of my invention, showing the position of the valve when both steam-ports are closed.

Figure 2 is a like view, showing the position of the valve, with the steam-ports at one end of the cylinder partly open.

Figure 3 is a like view, showing the position of the valve with the exhaust-ports of one side open.

The arrows in fig. 2 show the direction of the steam entering the cylinder.

The arrows in fig. 3 show the direction of the exhaust-steam.

Similar letters of reference indicate corresponding parts.

The valve-seat A is made in the ordinary way, and is furnished with the usual steam-ports, α and α^3 , and two ports opening into the exhaust-chamber D, as shown.

The valve B is furnished with two exhaust-chambers, C, and with the steam-passage α^1 , and with the two passages, α^2 , for the exhaust-steam, as shown in the drawing.

In the position of the valve shown in fig. 3, the steam is exhausting through the port α^3 and the passage α^2 , and also through the right chamber C, into the exhaust-chamber D.

The valve B is supposed to be moving to the right, or towards the port α^3 , and from the port α . It is obvious, therefore, that all the steam will have been exhausted from the right end of the cylinder before the port α is open to take steam. When the valve B has moved into the position as shown in the drawing, fig. 2, the steam-passage α^1 will be open to the steam at the right end of the valve, and open to the port α at the left end of the valve, the port α being also partially open directly to the steam in the steam-chest.

By the reverse motion of the valve B, the steam is exhausted through the left exhaust-passage α^2 and the left exhaust-chamber C, while steam is admitted to the cylinder through the passage α^1 and the port α^3 . The valve B thus serves as a cut-off also, and the steam is taken and exhausted by double openings.

The advantages of a valve so constructed are that the steam is both more freely admitted to and exhausted from a steam-engine cylinder than by the steam-valves now commonly in use.

I claim as new, and desire to secure by Letters Patent—

1. A steam-sliding valve, provided with two exhaust-chambers, C, and the two exhaust-steam passages α^2 , and the chambers C, in combination with the steam and exhaust-ports of any valve-seat, A, substantially as shown and described.

2. A steam-valve, provided with the steam-passage α^1 , and the exhaust-steam passages α^2 , and the chambers C, in combination with the steam and exhaust-ports of any valve-seat, A, substantially as shown and described, and for the purposes set forth.

The above specification of my invention signed by me, this day of , 186

WILLIAM WILSON.
